US00D671708S

(12) United States Design Patent
Hobel(10) Patent No.: US D671,708 S
(45) Date of Patent: * Dec. 4, 2012(54) BREAD PRODUCT

- (75) Inventor: Michael Hobel, Horschung (AT)
- (73) Assignee: Eat The Ball Holding GmbH, Salzburg (AT)
- () Term: 14 Years
- (21) Appl. No.: 29/402,376
- (22) Filed: Sep. 22, 2011

Primary Examiner — Barbara Fox*(74) Attorney, Agent, or Firm* — Alston & Bird LLP

- (57) CLAIM
The ornamental design for bread product, as shown and described.

DESCRIPTION

The patent or application file contains a drawing executed in color. Copies of this patent or patent application publication with the color drawing will be provided by the Office upon request and payment of the necessary fee.

The single FIGURE is a perspective view of a bread product showing my new design, the rear perspective view thereof being a mirror image.

1 Claim, 1 Drawing Sheet
